UNITED STATES PATENT OFFICE.

ALONZO W. BENNETT, OF NEW HAVEN, CONNECTICUT.

STEAM TURBINE.

Application filed December 23, 1926. Serial No. 156,586.

This invention relates to an improvement in steam turbines and has for its object the production of a simple, compact, and efficient steam turbine constructed with particular reference to simplicity of control.

With this object in view, my invention consists in a steam turbine characterized by a disk-like rotor having a series of buckets formed upon each of its opposite faces, a stator-fixture formed with two series of steam-return guides and two steam-nozzles and positioned adjacent the opposite faces of the rotor, so that one of the said series of return-guides and one of the said nozzles will act upon each face of the rotor, a passage connected to a steam-manifold for supplying steam to both of the said nozzles, and a valve for governing the entry of steam into the said passage for the concurrent control of both of the said nozzles.

In the accompanying drawings:

Fig. 1 is a view in side elevation of a steam turbine constructed in accordance with my invention;

Fig. 2 is an enlarged vertical central sectional view thereof on the line 2—2 of Fig. 1;

Fig. 3 is a broken plan view partly in section showing the rotor and two stator-fixture members in section; and

Fig. 4 is a view in inside elevation of the two complementary stator-fixture members detached.

In carrying out my invention, as herein shown, I provide the steam-turbine case 10 with a flanged inlet-port 11 leading into a ring-like steam-manifold 12 formed integral with the case 10. This steam-manifold 12 serves to supply steam to a number of corresponding pairs of stator-fixture members, more or less in number, a description of one pair serving for all.

The inner wall 13 of the manifold 12 is formed with a passage 14 for the reception of the threaded shank 15, of a stator-fixture member 16 constituting one of a complementary pair, the shank 15 being secured in place in the wall 13 by means of a lock-nut 17.

The outer end of the shank is formed with a rounded, circular, offset seat 18 with which a valve-washer 19, mounted at the inner end of a valve-stem 20, co-acts. The said valve-stem is provided with a hand-wheel 21 and is threaded as at 22 for co-action with the internal threads of a valve-bonnet 23 mount-

ed in the outer wall 24 of the manifold 12 and provided with a packing-gland 25 to prevent the escape of steam past the valve-stem 20.

Extending through the stator-fixture member 16 is a substantially S-shaped passage 26 leading inward through the shank 15, thence outward and again inward to the inner face of the member, where it registers with an L-shaped passage 27 formed in a stator-fixture member 28 complementing the member 16, to which it is secured by bolts 29 (Fig. 1) passing through holes 30 formed in the respective members.

By reference to Fig. 2 of the drawings, it will be seen that the S-shaped passage 26 of the stator-member 16 and the L-shaped passage 27 of the stator-member 28 in effect constitute one passage bowed outward around the periphery of the turbine rotor 31, which, as shown, is formed upon each of its opposite faces, near its periphery, with a series of buckets 32 and 33 respectively.

For the purpose of directing steam into the buckets 32, the steam-passage 26 of the stator-member 16 is intersected by a passage 34, which in effect constitutes one of the nozzles of my improved turbine, the orifice 35 being in line with the inner edges of the buckets, as is the common practice, so that the steam initially impinges against the inner ends of the buckets 32 and is by them deflected into the return-guides 36 of the stator-member 16 by means of which the jet of steam is caused to repeatedly impinge and reimpinge against the buckets 32 as they pass by the member.

Similarly, the buckets 33 of the rotor 31 are acted upon by the steam which flows out of the L-shaped passage 27 of the member 28, through a passage 37 corresponding to the passage 34, which has its orifice 38 located with respect to the buckets 33 in the same manner as that of the orifice 35, with the exception that it is on the opposite side of the rotor.

While I have shown and described the members 16 and 28 as separate elements, I wish to have it understood that they may be formed in one piece, though I prefer the construction shown because of its ease of manufacture and facility of assembly.

From the foregoing, it will be seen that by my invention I am enabled to control the flow of steam against the opposite sides of the rotor 31 by means of a single valve,

thereby not only securing the advantages of simplified control, but greatly reducing the complexity of the turbine by dispensing with the need for two steam manifolds, as is necessary in prior turbines of the same general type.

I claim:

1. A steam turbine, comprising a casing; a rotor-chamber formed therein; a steam-manifold chamber also formed in said casing adjacent the said rotor-chamber; a partition-wall between the two said chambers; a rotor mounted in said rotor-chamber; a two-part stator-fixture formed independent of the casing and having its parts respectively located within the casing on the opposite sides of the rotor and each provided with a nozzle for directing steam against the adjacent face of the said rotor; a steam-passage traversing the two-part stator-fixture and passing through the said partition-wall; and a valve-stem and closure for controlling the flow of steam from the said manifold to the said nozzles.
2. A steam turbine, comprising a casing; a rotor-chamber formed therein; a steam-manifold chamber also formed in said casing adjacent the said rotor-chamber; a partition-wall between the two said chambers; a rotor mounted in said rotor-chamber; a stator-fixture adapted to straddle the rotor

and having nozzles located on opposite sides thereof; a hollow shank formed on the said stator-fixture and passing through the said partition-wall; a steam-passage formed in the said stator-fixture for connecting the said hollow shank with the said nozzles; a valve-stem mounted in the outer wall of the manifold in line with the said hollow shank; and a closure carried by the said stem for co-action with the outer end of the hollow shank for controlling the flow of steam from the manifold to the said nozzles.

3. In a steam turbine, the combination with the rotor and steam-manifold chamber thereof; of an independently-formed stator-fixture adapted to straddle the periphery of the rotor and having nozzles located on opposite sides of the rotor and directed against the opposite faces thereof; a passage formed in the said stator-fixture and leading from the manifold to the said nozzles; and a valve for governing the flow of steam from the manifold into the said passage; whereby the flow of steam from the said manifold to the said nozzles on opposite sides of the rotor is concurrently governed by means of the said valve.

In testimony whereof, I have signed this specification,

ALONZO W. BENNETT.
